[57] CLAIM

The ornamental design for a pair of trousers, as shown
and described.

DESCRIPTION

FIG. 1 is a front elevational view of a pair of trousers
showing my new design in the position of use;

FIG. 2 is a rear elevational view thereof;

FIG. 3 is a right side elevational view thereof, the left
side being a substantial mirror image;

FIG. 4 is a front elevational view of an alternate em-
bodiment of the design shown in FIG. 1;

FIG. 5 is a rear elevational view of FIG. 4;

FIG. 6 is a right side elevational view of FIG. 4, the left
side being a substantial mirror image;

FIG. 7 is a front elevational view of a second embodi-
ment of the design shown in FIG. 1;

FIG. 8 is a rear elevational view of FIG. 7; and

FIG. 9 is a right side elevational view of FIG. 7, the left
side being a substantial mirror image.

The shaded areas in FIGS. 2, 3, 5, 6, 8 and 9 represent
fabric contrast.
